(57) **CLAIM**

The ornamental design for a saddle bag for a bicycle, as shown and described.

DESCRIPTION

FIG. 1 is a front perspective view of the saddle bag for a bicycle according to an alternative embodiment; FIG. 2 is a top plan view of the embodiment of FIG. 1; FIG. 3 is a front elevation view of the embodiment of FIG. 1; FIG. 4 is a right elevation view of the embodiment of FIG. 1; FIG. 5 is a left elevation view of the embodiment of FIG. 1; FIG. 6 is a rear elevation view of the embodiment of FIG. 1; and,

FIG. 7 is a bottom plan view of the embodiment of FIG. 1. The broken line showing of a saddle bag for a bicycle is included for the purpose of illustrating environment and forms no part of the claimed design.
